UNITED STATES PATENT OFFICE.

DANIEL D. MILLER, OF NEW YORK, N. Y., ASSIGNOR TO WESTERN ELECTRIC COMPANY, INCORPORATED, OF NEW YORK, N. Y., A CORPORATION OF NEW YORK.

RELAY.

Application filed September 6, 1924. Serial No. 736,381.

To all whom it may concern:

Be it known that I, DANIEL D. MILLER, a citizen of the United States, residing at New York, in the county of New York, 5 State of New York, have invented certain new and useful Improvements in Relays, of which the following is a full, clear, concise, and exact description.

This invention relates to voice frequency 10 relays and more particularly to relays of this type for controlling electrical circuits.

The object of this invention is to provide an improved relay of this character, wherein in the energization of a coil or a plurality 15 of windings positioned in a magnetic field, serves to actuate an associated coil which in turn controls a secondary circuit.

Another object of this invention is to provide means whereby a circuit including a 20 source of alternating current and a coil or plurality of windings positioned in a magnetic field, may be so related to another coil not connected to any source of current, and differently positioned in the same magnetic 25 field, that the effect of said first circuit upon said coil is to control another circuit.

To attain these objects, a feature of the invention resides in the provision of a relay having a coil positioned in the magnetic 30 field thereof and adapted to be energized by voice frequency currents, and a second coil, closed upon itself, and movably suspended in said field from contacts to be controlled. Thus, the energization of the first 35 coil, induces vibration of the second coil in said field to open the contacts, and thereby break a normally closed circuit.

Another feature of the invention comprises a relay having serially connected 40 windings on a closed magnetic core, wherein in the leakage flux produced by the energization of said windings, actuates a movable closed circuit coil interlinked with said core between said windings and supported from 45 contacts to be controlled. Vibration of the movable coil due to energization of the serially connected windings, causes the opening of contacts, hence breaking a normally closed circuit.

50 Other and further features will be understood from the following description of the invention in conjunction with the accompanying drawing in which Fig. 1 shows a cross-section view of relay illustrating the

invention together with circuits therefor; 55 Fig. 2 illustrates a plan or top view of the relay shown in Fig. 1; while Fig. 3 is illustrative of a relay having a closed magnetic core on which two spaced and serially connected windings are positioned between 60 which a short-circuited coil loosely encircling the core is sufficient for contacts to be controlled.

Referring to Figs. 1 and 2, a cup shaped 65 electromagnet structure is shown having a magnetizing winding 18 energized by battery 14 surrounding its central pole 1. Suitably attached to the upper extremities of pole 2, and diametrically opposed to each other are insulating blocks 3 and 4 which 70 serve as supports for hook eye terminals 5 and 6. Terminals 5 and 6 at their eyes 8 and 9 respectively, loosely support hook ended contact member 7, to which in turn is rigidly attached, at points 10 and 11, a 75 light closed circuit coil 12 which loosely encircles the upper end 13, of the core 1 of the electromagnet. Immediately below coil 12 and suitably spaced therefrom is rigidly positioned another coil 15, which is energized by a source of alternating current 16 80 upon the closure of the circuit in any suitable manner.

The operation of the relay shown in Fig. 1 will now be described. 85

Coil 15, which is rigidly positioned in the magnetic field of electromagnet 1, is energized when alternating current is supplied from source 16. Upon the energization of coil 15, closed circuit coil 12 will vibrate 90 up and down in accordance with the frequency of the applied current, to open the normally closed contacts 8 and 9, and break the circuit to be controlled which includes grounded battery, relay 17, terminal 6, contacts 9 (where the hook eye extremity of terminal 6 meets the hook extremity of contact member 7) contact member 7; contacts 8, terminal 5, to ground. 95

Hence, when coil 15 is energized, coil 12 100 is caused to vibrate and thus intermittently opens contacts 8 and 9 to break the electrical continuity of the normally closed circuit containing relay 17. When the current from source 16 is cut off, coil 15 will de- 105 energize, coil 12 will thereupon cease vibrating, the contact member 7 restores to normal at contacts 8 and 9, due to the nat-

ural force of gravity on coil 12, and the circuit restores to its normally closed condition.

Considering the relay shown in Fig. 3, 20 illustrates a closed magnetic core consisting of a U shaped magnet 40, having a "keeper" 20 closing its two polar extremities. 21 and 22 represent respectively two spaced and serially connected stationary windings on keeper 20 adapted to be energized by voice frequency currents from source 23. Between windings 21 and 22, is had a movable closed circuit coil 24, loosely encircling keeper 20.

Coil 24 is suspended from contact members 25 and 26 which are fastened at points 27 and 28 respectively to the coil. The extremities of contact members 25 and 26 are in the form of hooked-eyes, and fit into, similarly ended respective terminals 29 and 30. The terminals 29 and 30 are rigidly supported by insulated member 31, securely fastened on the keeper 20 of other suitable support.

When alternating current from source 23 is supplied to the serially connected windings 21 and 22, movable coil 24 will vibrate up and down between these windings in accordance with the frequency of the applied current. In vibrating, the coil 24 will cause contact members 25 and 26 to similarly vibrate and thus break contact with terminals 29 and 30 at contacts 33 and 34. In breaking contact thereat, the following normally closed circuit will be broken: grounded battery, relay 35, terminal 30, contact 34, contact member 26, conductor 36, contact member 25, contacts 33, terminal 29 to ground.

When source 23 ceases to supply current to the windings 21 and 22 they will deenergize, coil 24 will cease vibrating and due to gravity remake contact at points 33 and 34. The circuit will then restore to its normally closed position.

What is claimed is:

1. An electromagnet structure having a coil rigidly positioned in the polar field thereof, a second coil loosely positioned in the polar field thereof, and means comprising an alternating current source for energizing said first coil to cause said second coil to vibrate.

2. An electromagnet structure comprising a core, a coil rigidly positioned about the upper extremity thereof, mountings insulated from said structure, a second coil suspended from said mountings and loosely disposed about said core in superposition to said first coil, an alternating current source for energizing said first coil to cause said second coil to vibrate.

3. An electromagnet structure comprising a core, a coil rigidly positioned about the upper extremity thereof, mountings insulated from said structure, a second coil suspended from said mountings and loosely

encircling said core in superposition to said first coil, a plurality of contacts normally closed by said second coil, an alternating current source for energizing said first coil to cause said second coil to vibrate and intermittently open and close said contacts.

4. A relay comprising a magnet, a coil rigidly positioned in the magnetic field thereof and adapted to be energized by voice frequency currents, a second coil closed upon itself, and movably suspended in said field from contacts controlled thereby, whereby said second coil is moved up and down in said field to open and close said contacts in response to the energization of said first coil by second voice frequency current.

5. A switching device comprising a magnet, a coil connected to a source of alternating current and rigidly positioned in the polar field created by said magnet, a circuit to be controlled and terminals therefor, a contact device loosely resting upon and electrically connecting said terminals and a second coil mounted upon said contact device and also positioned in said polar field.

6. In combination, a switching device comprising a magnet, a circuit to be controlled, terminals therefor, a contact member making contact with said terminals to close said circuit, a coil mounted on said contact member and positioned in the magnetic field created by said magnet and a second coil rigidly mounted in said magnetic field and adapted to be connected to a source of alternating current.

7. A switching device comprising a magnet, a circuit to be controlled and terminals therefor, means including a coil for closing said circuit at said terminals, and a second coil connected to a source of alternating current arranged when energized to cause said first coil to vibrate and open said circuit at said contacts.

8. In a switching device, a magnet, a vibratory device including a coil mounted thereon and suspended in the magnetic field created by said magnet, a second coil, and means comprising a source of alternating current for energizing said second coil to cause said vibratory device to function.

9. In a switching device, a first circuit, terminals therefor, contact members loosely making contact with said terminals means including a vibratory device and a coil mounted thereon for normally maintaining said circuit closed, and means including a second coil for actuating said first coil to open said circuit at the contacts of said contact members and terminals.

10. In a switching system, a relay comprising a magnet, a first coil rigidly positioned in the magnetic field thereof and connected to a source of alternating current, terminals rigidly fixed, a contact member loosely engaged at its extremities by said

- terminals, a second coil mounted on said contact member and suspended therefrom in superposition to said first coil and spaced therefrom, a circuit normally closed by said 5 contact member at said terminals, a second circuit including a source of alternating current connected to said first coil, and means for applying said current to said first coil through said second circuit to cause said 10 second coil to vibrate in accordance with the frequency of said current, and break said first circuit at the contacts of said contact member and terminals.
11. A closed magnetic core, a plurality of 15 serially connected windings, a source of alternating current adapted to be connected to said windings, and means including a coil positioned between said windings and surrounding said core adapted to vibrate 20 upon the energization of said windings by said source of current to control a local circuit.
12. In a relay, a closed magnetic core, two serially connected stationary windings, 25 a movable closed circuit coil loosely encircling said core between said windings, a circuit normally closed by said coil at a plurality of contacts, and a source of alternating current for energizing said windings 30 to cause said coil to alternately move up and down on said core to break said circuit.
13. In a circuit control system, a closed magnetic core, two serially connected windings on said core, a circuit, terminals therefor, a closed circuit coil loosely encircling 35 said core between said windings and normally closing said circuit at contact members attached thereto, and means comprising a source of alternating current for energizing 40 said windings to cause the vibration of said coil to break said circuit.
14. In a circuit control system, a first circuit comprising two serially connected windings about a closed magnetic core and 45 a source of alternating current, a second circuit including rigidly positioned terminals,
- and a coil encircling said core and loosely suspended between said windings from said terminals by contact members attached to said coil, said contact members being 50 adapted to close said second circuit when they are in engagement with said terminals, whereby the energization of said windings by said source of current causes said coil to vibrate in accordance with the frequency 55 thereof, to break said second circuit at the front contact of said contact members and terminals.
15. A magnetic structure comprising means positioned in the magnetic field thereof for actuating a coil loosely mounted and normally in contact at a plurality of points to close an electrical circuit. 60
16. A magnetic structure comprising means rigidly positioned in the polar field thereof, a source of alternating current adapted to be connected to said means, a coil, loosely mounted and having means attached thereto for normally making contact with rigidly fixed terminals, said coil being actuated upon the energization of said means to vibrate in accordance with the frequency of the applied current to break 65 said contacts. 70
17. A relay comprising a closed magnetic core, an energizing winding interlinked with said core, a closed secondary winding interlinked with said core and contacts operated by said secondary winding. 75
18. A relay comprising a closed magnetic core, a primary winding of said relay, a secondary winding loosely associated with said core, said windings being so constructed and arranged that said secondary winding is energized by the leakage flux produced by 80 said primary winding, and contact controlled by said secondary winding. 85

In witness whereof, I hereunto subscribe my name this 3 day of September A. D., 1924.

DANIEL D. MILLER.
